UNITED STATES PATENT OFFICE.

HARVEY B. WILSON, OF DEWITT, ILLINOIS.

CRANK HOLDER.

1,419,793.

Specification of Letters Patent. Patented June 13, 1922.

Application filed May 14, 1920. Serial No. 381,315.

To all whom it may concern:

Be it known that I, HARVEY B. WILSON, a citizen of the United States, residing at Dewitt, in the county of De Witt and State 5 of Illinois, have invented a new and useful Crank Holder, of which the following is a specification.

The present invention has reference to guards or, shields for radiators, of internal 10 combustion engines, and it is the primary object of the invention to provide a radiator guard which may be readily and easily applied to the radiator of a tractor or the like to guard the tubes of the radiator, against 15 damage by encountering obstructions.

A further object of the invention is the provision of means carried by the guard to support the crank handle of the motor in a vertical position, in a manner to prevent 20 movement thereof when the device is in operation.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 within the scope of what is claimed, without departing from the spirit of the invention.

Referring to the drawing:—

Figure 1 is a front elevational view of a radiator showing the invention as applied 30 thereto.

Figure 2 is a side elevational view of the same, the radiator being shown in dotted lines; and

Figure 3 is a plan view of the crank handle supporting means, forming a part of the invention.

Referring to the drawing in detail, the radiator to which the invention is applied, is indicated by the reference character 5, the 45 same being shown in dotted lines and provided with the flanges 6 and 7 disposed at the upper and lower ends respectively thereof.

The radiator guard, forming the subject 50 matter of the present invention includes an upper bar 8 and a lower bar 9, each of which

is provided with an inwardly disposed extension 10, formed at the respective ends thereof, which extensions are apertured to receive the bolts 11, which pass through suitable registering openings formed in the flanges 6 and 7 respectively, thus providing means for securing the guard to the radiator.

Forming the body portion of the guard, 60 are a plurality of vertically disposed rods 12, arranged in transverse spaced relation with each other, the end bars of the body portion lying in planes flush with the side walls of the radiator to which the guard is 65 applied so that the entire front surface of the radiator is guarded.

In order that the rods 12 may be maintained in suitable spaced relation with each other, a transversely extending bar 13 is 70 provided and has connection with the respective rods 12 intermediate the ends thereof, so that the central portions of the rods 12 will be restricted against movement with relation to each other.

The securing plate, which is substantially triangular in formation, is indicated by the reference character 14, and as shown, this securing plate is provided with an eye elongated opening 15 adapted to accommodate 80 one of the rods 12 of the body portion of the guard, the shoulders 16 of the plate contacting with the rods adjacent to the rod which has connection with the plate 14, so that lateral movement of the plate 14, when 85 the device is in a securing position, is absolutely prevented.

One portion of the plate 14, is cut away as at 17, to accommodate the usual crank arm, forming a part of the motor vehicle so 90 that the crank arm will be maintained in an upright position, and prevented from being thrust into engagement with the drive shaft of the motor, associated with the crank arm.

It is believed that in view of the foregoing 95 description, the operation and utility of the guard will be obvious and that further description as to the operation of the device, is unnecessary.

Having thus described the invention, what 100 is claimed as new is:—

In combination with vertically disposed

rods, a retaining device for crank handles including a plate, said plate having shoulders and having an eye adapted to accommodate one of the vertically disposed rods, the 5 shoulders adapted to contact with the adjacent rods, and said plate having a notched portion to accommodate a cranking handle.

In testimony that I claim the foregoing as my own, I have hereto affixed my signature in the presence of two witnesses.

HARVEY B. WILSON.
